(57) **CLAIM**

The ornamental design for a portable USB memory holder, as shown.

DESCRIPTION

FIG. 1 is a front elevational view of the present invention; FIG. 2 is a right side elevational view, the left side being a mirror image thereof;

FIG. 3 is a rear elevational view;

FIG. 4 is a top plan view;

FIG. 5 is a bottom plan view;

FIG. 6 is a front elevational view of the present invention with a cover being removed therefrom;

FIG. 7 is a right side elevational view with the cover being removed therefrom, the left side being a mirror image thereof;

FIG. 8 is a rear elevational view with the cover being removed therefrom; and,

FIG. 9 is a top plan view with the cover being removed therefrom.

The broken line showing of an upstream port is for illustrative purposes only and forms no part of the claimed design.
